CLAIM

The ornamental design for an end frame for a bench, as shown and described.

DESCRIPTION

FIG. 1 is an isometric view of an end frame for a bench showing my new design.

FIG. 2 is a right side elevational view of the end frame for a bench of FIG. 1, the left side elevational view being a mirror image thereof.

FIG. 3 is a front elevational view of the end frame for a bench of FIG. 1, the rear elevational view being a mirror image thereof.

FIG. 4 is a top plan view of the end frame for a bench of FIG. 1; and,

FIG. 5 is a bottom plan view of the end frame for a bench of FIG. 1.

1 Claim, 1 Drawing Sheet
